PORTABLE SHELF

Anton U. Peterson, Chicago, Ill.

Application March 27, 1947, Serial No. 737,521

11 Claims. (Cl. 211—93)

1

The invention provides a construction of portable shelf that may readily and quickly be mounted on a wall when wanted for use, and that may easily and at once be removed from the wall when the shelf is not needed, the shelf being provided with supporting legs which may then be folded against the body member of the shelf to reduce the structure to small compass for storage until the shelf is again needed. The shelf may be repeatedly mounted on a wall and removed therefrom, as many times as desired, and without the use of special tools.

More specifically, the shelf of the invention includes a body member for supporting desired articles, from the rear or wall edge of which a first flange extends downwardly at substantially a right angle to facilitate mounting the shelf on a wall by means of specially constructed hooks secured to the wall, said body member having also a second flange extending downwardly and rearwardly at an oblique angle from its front or outer edge, to which second flange supporting legs are pivotally connected to extend when in opened position, downwardly and rearwardly to engage the wall at their lower ends. The obliquity of the second flange imparts proper direction to said legs to engage the wall as described, and when the shelf is not in use, the legs may be folded against said second flange to reduce the entire thickness of the structure to the width of said flanges for storage purposes.

The shelf of the invention is constructed to support loads of different amounts, and where the load is light, the structure thus far described, is found to operate satisfactorily. To provide for supporting relatively heavy loads, tension members are provided between the lower ends of the legs and the body member of the shelf, to prevent the lower ends of the legs from slipping downwardly on the wall, which action might otherwise occur when the shelf is heavily loaded.

The body member of the shelf is preferably made of sheet material such as metal, and the legs are preferably made of similar material, the said tension members being preferably metal rods or wires or the equivalent, as a result of which the entire shelf structure is of simple and inexpensive construction, although entirely satisfactory for its intended purposes, for example, for use generally in houses where the convenience of supporting small or relatively light articles is desired, and particularly where said desired use is temporary and subject to repetition making the repeated removal and replacement of the shelf desirable.

It is the object of the invention to produce a shelf having the construction, operation and advantages described.

The above and further objects of the invention, will be best understood by reference to the accompanying drawings illustrating a preferred embodiment thereof, in which

2

Fig. 1 shows the shelf in plan view mounted on a wall,

Fig. 2 is an end view in elevation of the structure shown in Fig. 1,

Fig. 3 shows in a view similar to Fig. 2, the shelf removed from the wall and with its legs folded against its front flange,

Fig. 4 is a bottom view of the front flange of the shelf with its legs folded against said front flange, this view being taken along the line 4—4 in Fig. 3,

Fig. 5 is a detail sectional view to an enlarged scale of a part of the structure shown in Fig. 1, taken along the line 5—5 in Fig. 1, and

Fig. 6 is a detail sectional view to an enlarged scale of a part of the structure shown in Fig. 1, taken along the line 6—6 in Fig. 1.

Similar numerals refer to similar parts throughout the several views.

As shown in Figs. 1 and 2, the shelf includes a flat body member 10 made preferably of sheet material such as metal or the equivalent, of a thickness adapted to carry a desired load without deformation. A rear flange 11 integral with the body member 10, extends vertically in contact with a wall 12 when the shelf is in use with the body member 10 in horizontal position, as illustrated. A front flange 13 integral with the body member 10, extends downwardly and rearwardly from said body member, and has pivotally connected with it at 14 and 15, the upper ends of legs 16 and 17 respectively, having their lower ends in engagement with the wall 12 to support the front or outer edge of the body member 10. The legs 16 and 17 preferably have the same inclination to the body member 10, as has the flange 13, to facilitate folding said legs against said flange as shown in Figs. 3 and 4, when the shelf is removed from the wall. The lower ends of the legs 16 and 17 are preferably coated with friction material 18 and 19, such as soft rubber or semi-adhesive compound, to resist downward movement of the lower ends of the legs on the wall 12, when a load is placed on the shelf.

The flange 11 is supported on the wall 12, by a special form of hook 20, two of which are shown in Fig. 1. Each of the hooks 20 is preferably constructed of sheet metal as shown in Fig. 5, and has a folded upper end provided with spaced holes 50 to receive a supporting nail 21, by which the nail is held at an effective supporting inclination while being driven into the wall 12, and by which the nail is retained in that inclination when the hook has been firmly mounted on the wall by said nail. The flange 11 is provided with a clearance opening 22 for the upper portion of each of said hooks. The bottom of each of said openings 22 is closed by a distended portion of the flange 11 forming a loop 23 for engaging the lower and upwardly opening hook-shaped portion of the corresponding hook 20 to support the flange 11 and in turn the rear portion of the shelf (see Fig. 5).

The flange 11 is preferably provided with a plurality of integral hooks 24 formed from said flange (see Figs. 1 and 2) to support articles under the shelf when the same is in use.

Widely differing amounts of load may be supported by the shelf by suitably proportioning the parts thereof. Where only a relatively light load is to be supported, the body member 10 and the legs 16 and 17 may be of relatively thin sheet material. Where the shelf is required to support substantially heavier loads, said body member and legs may be of sheet material having substantial inherent stiffness and they may be taken of sufficient thickness to resist deformation for the substantial downward thrusts on the lower ends of the legs, which may then be sufficient to overcome the friction of the lower ends of the legs on the wall. In some cases the load to be supported may be so heavy as to require additional support for the lower ends of the legs to avoid the necessity of making the body member 10 and legs 16 and 17 unduly thick and heavy.

To provide for cases of heavy loading of the shelf, tension members 25 and 26 are shown, which at their lower ends articulate with the lower end portions of the legs 16 and 17, and at their upper ends are slidably supported by off-set rods 27 and 28 rigidly secured to the lower surface of the body member 10, for example, by welding, to permit the folding of the legs, as described, against the flange 13. The tension members 25 and 26 under heavy loads on the shelf, support the lower ends of the legs 16 and 17 against the downward thrusts exerted on them in excess of the friction between the legs and the wall 12, and are illustrative only, since any equivalent devices may be employed that will similarly support the legs and permit the same to be folded against the flange 13. Said members being subjected only to tension, they may consist of slender steel rods or equivalent tension members, and they may be dispensed with where the shelf is to be used to support light loads only.

To facilitate mounting the shelf on a wall, gauge marks 29 are made on its upper surface (see Fig. 1), and the shelf with its body member in horizontal position, is placed against the wall a little below the height desired for the shelf, and marks are made on the wall at the wall ends of the gauge marks 29; then the shelf is removed from the wall, and the nails 21 extending through the hooks 20 are driven into the wall at the marks so made thereon, and at the inclination required by the hooks to firmly seat them flat against the wall in proper supporting position, which inclination is preferably substantially 45 degrees with the wall surface and effectively engages the nails with the wall for load supporting purposes and in a manner preventing the nails from accidentally becoming loose and dropping from the wall; all that is then required to mount the shelf, is to engage the loops 23 of the flange 11 in the hooks 20 and to extend the legs 16 and 17 to their open or lower position. The hooks 20 may remain permanently on the wall, and the removal of the shelf requires only the folding of the legs from their open position and the lifting of the loops 23 from engagement with the hooks 20. The folding of the legs against the flange 13 reduces the bulk of the shelf to a minimum for storage until the shelf is again needed for use, and it also facilitates compact packaging for sale purposes.

The simple described construction of the shelf

makes it inexpensive to manufacture, without in any way detracting from its convenience in mounting on a wall and removal therefrom, and without in any way decreasing its effectiveness in use.

It will be understood that the shelf construction described is illustrative of a preferred embodiment of the invention, and that the parts of the shelf shown, for example, the supporting hooks, the folding legs and the tension members, may be replaced by equivalent structures having similar modes of operation, without departing from the scope of the invention. I do not therefore limit myself in carrying out the invention to the particular structure shown and described, as I may employ equivalents thereof without departing from the scope of the appended claims.

What I claim is:

1. In a portable shelf, the combination of a body member having an integral rear flange for engagement with a wall and having an integral front flange extending downwardly and rearwardly at an oblique angle from the front edge of said body member, spaced legs pivotally connected at their upper ends with said front flange and when open extending downwardly and rearwardly from said front flange for engagement at their lower ends with a wall, and separable means for securing said rear flange to a wall, said legs being movable to a folded position adjacent said front flange for storage purposes.

2. In a portable shelf, the combination of a body member having an integral rear flange for engagement with a wall and having an integral front flange extending downwardly and rearwardly at an oblique angle from the front edge of said body member, spaced legs pivotally connected at their upper ends with said front flange and when open extending downwardly and rearwardly from said front flange for engagement at their lower ends with a wall, and separable means for securing said rear flange to a wall, said legs being movable to a folded position adjacent said front flange for storage purposes, said legs at their lower ends carrying friction material for engaging said wall and tending to avoid slipping of said lower leg ends on said wall.

3. In a portable shelf, the combination of a body member having an integral rear flange for engagement with a wall and having an integral front flange extending downwardly and rearwardly at an oblique angle from the front edge of said body member, spaced legs pivotally connected at their upper ends with said front flange and when open extending downwardly and rearwardly from said front flange for engagement at their lower ends with a wall, and separable means for securing said rear flange to a wall, said legs being movable to a folded position adjacent said front flange for storage purposes, said legs at their lower ends having coatings of semi-adhesive material for engaging said wall.

4. In a portable shelf, the combination of a body member having an integral rear flange for engagement with a wall and having an integral front flange extending downwardly and rearwardly at an oblique angle from the front edge of said body member, spaced legs pivotally connected at their upper ends with said front flange and when open extending downwardly and rearwardly from said front flange for engagement at their lower ends with a wall, and separable means for securing said rear flange to a wall, said legs being movable to a folded position adjacent said front flange for storage purposes, said legs at

their lower ends having coatings of soft rubber compound for engaging said wall.

5. In a portable shelf, the combination of a body member having an integral rear flange for engagement with a wall and having an integral front flange extending downwardly and rearwardly at an oblique angle from the front edge of said body member, spaced legs pivotally connected at their upper ends with said front flange and when open extending downwardly and rearwardly from said front flange for engagement at their lower ends with a wall, and separable means for securing said rear flange to a wall, said legs being movable to a folded position adjacent said front flange for storage purposes, said supporting means including upwardly opening hooks for connection with said wall, said rear flange having clearance openings below the level of said body member for receiving said hooks.

6. In a portable shelf, the combination of a body member having an integral rear flange for engagement with a wall and having an integral front flange extending downwardly and rearwardly at an oblique angle from the front edge of said body member, spaced legs pivotally connected at their upper ends with said front flange and when open extending downwardly and rearwardly from said front flange for engagement at their lower ends with a wall, and separable means for securing said rear flange to a wall, said legs being movable to a folded position adjacent said front flange for storage purposes, said supporting means including upwardly opening hooks for connection with said wall, said rear flange having clearance openings below the level of said body member for receiving said hooks, the portions of said rear flange engaging said hooks being off-set away from the wall to clear the body portions of said hooks.

7. In a portable shelf, the combination of a body member having an integral rear flange for engagement with a wall and having an integral front flange extending downwardly and rearwardly at an oblique angle from the front edge of said body member, spaced legs pivotally connected at their upper ends with said front flange and when open extending downwardly and rearwardly from said front flange for engagement at their lower ends with a wall, separable means for securing said rear flange to a wall, said legs being movable to a folded position adjacent said front flange for storage purposes, and means for supporting the lower ends of said legs from said body member for the open position of said legs.

8. In a portable shelf, the combination of a body member having an integral rear flange for engagement with a wall and having an integral front flange extending downwardly and rearwardly at an oblique angle from the front edge of said body member, spaced legs pivotally connected at their upper ends with said front flange and when open extending downwardly and rearwardly from said front flange for engagement at their lower ends with a wall, separable means for securing said rear flange to a wall, said legs being movable to a folded position adjacent said front flange for storage purposes, and means for supporting the lower ends of said legs from said body member for the open position of said legs, said means including tension members pivotally connected at their lower ends with the lower ends of said legs and slidably connected at their upper ends with said body member.

9. In a portable shelf, the combination of a body member having an integral rear flange for

engagement with a wall and having an integral front flange extending downwardly and rearwardly at an oblique angle from the front edge of said body member, spaced legs pivotally connected at their upper ends with said front flange and when open extending downwardly and rearwardly from said front flange for engagement at their lower ends with a wall, separable means for securing said rear flange to a wall, said legs being movable to a folded position adjacent said front flange for storage purposes, and means for supporting the lower ends of said legs from said body member for the open position of said legs, said means including tension rods articulating at their lower ends with the lower ends of said legs, and slide members secured to said body member and extending towards said leg pivots and having sliding engagement with the upper ends of said rods to support the same.

10. In a portable shelf, the combination of a body member having a front flange extending downwardly and rearwardly at an oblique angle from the front edge of said body member, means for supporting the rear portion of said body member from a wall, spaced legs pivotally connected at their upper ends with said front flange and when open extending downwardly and rearwardly from said front flange for engagement at their lower ends with a wall, said legs being movable to a folded position adjacent said front flange for storage purposes, and means for supporting the lower ends of said legs from said body member for the open position of said legs, said means including tension members pivotally connected at their lower ends with the lower ends of said legs and slidably connected at their upper ends with said body member.

11. In a portable shelf, the combination of a body member having a front flange extending downwardly and rearwardly at an oblique angle from the front edge of said body member, means for supporting the rear portion of said body member from a wall, spaced legs pivotally connected at their upper ends with said front flange and when open extending downwardly and rearwardly from said front flange for engagement at their lower ends with a wall, said legs being movable to a folded position adjacent said front flange for storage purposes, and means for supporting the lower ends of said legs from said body member for the open position of said legs, said means including tension rods articulating at their lower ends with the lower ends of said legs, and slide members secured to said body member and extending towards said leg pivots and having sliding engagement with the upper ends of said rods to support the same.
